UNITED STATES PATENT OFFICE.

GEORGE M. WILLIS, OF CHICAGO, ILLINOIS, ASSIGNOR, BY DIRECT AND MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

ENGINE-STARTER.

1,246,690.

Specification of Letters Patent. Patented Nov. 13, 1917.

Application filed September 11, 1913. Serial No. 789,244.

To all whom it may concern:

Be it known that I, GEORGE M. WILLIS, a citizen of the United States, residing at Chicago, in the county of Cook and State of Illinois, have invented certain new and useful Improvements in Engine-Starters, of which the following is a full, clear, concise, and exact description, reference being had to the accompanying drawings, forming a part 10 of this specification.

My invention relates to starters for engines which require the application of some external force to initiate their operation, such devices being commonly employed in 15 connection with internal combustion engines to eliminate the necessity of starting the engine by hand.

More particularly, my invention relates to electric starters and contemplates an equipment or system wherein an electric motor is thrown into operation and operative relation to the engine to be started by the closing of a switch, and wherein the motor is automatically disconnected from the engine after the latter has developed its own power.

I have illustrated an embodiment of my invention, together with certain modifications, in the accompanying drawings, and 30 in these drawings—

Figure 1 is a plan view, certain parts being represented diagrammatically.

Fig. 2 is a view similar to Fig. 1 except that a certain modification has been illustrated in addition.

Fig. 3 shows a modified form of the clutch.

Fig. 4 shows another modified form of the clutch.

Fig. 5 is a detail view of one of the parts shown in Fig. 4.

Fig. 6 is a further modification of one of the clutch parts.

Fig. 7 shows a rearrangement of the parts 45 of Fig. 1.

Figs. 8 and 9 show another rearrangement of the parts of Fig. 1.

Figs. 10 and 11 show still another arrangement of the parts of Fig. 1.

Fig. 12 shows a further modification.

Fig. 13 shows a further modification.

Referring first to Fig. 1, it will be seen that I provide an electric motor 12 and a

generator 13 bound together in axial alignment by means of straps 14, 14 in order 55 to form a structural unit. The motor shaft 15, shown in dotted lines, is mounted in the motor bearings 16, 16, and the generator shaft 17, shown in dotted lines, is mounted in the generator bearings 18, 18. For reasons which will more fully appear hereinafter, I prefer that the motor 12 shall be a direct current series wound motor, and it will be seen that I have diagrammatically 65 illustrated such a motor circuit in the arrangement now being described. The field windings are connected at 19, 19, the armature winding is connected at 20, and the commutator and brushes at 21 and 22 respectively. 70

The generator is preferably of the direct current shunt wound type and I have illustrated a generator armature winding 23 connected to the commutator 24 which, in turn, is engaged by the brushes 25, 25 connected in 75 shunt of the field windings 26, 26.

The shaft 17 of the generator extends for a considerable distance beyond the bearing 18 and toward the motor, and upon this shaft extension a pulley wheel 27 is secured. 80 This pulley wheel is permanently connected with the fly-wheel of the engine, this fly-wheel being illustrated at 28, by means of a noiseless chain belt 29. Also mounted upon this shaft extension is the clutch disk 85 30, which is capable of slight longitudinal movement on the shaft 17 but always turns with the shaft, this being secured by means of a feather 31. A spring 32 is connected with the clutch disk member and also with the pulley member, and tends to hold the clutch disk 30 tightly up against the pulley member in a position which I shall refer to hereinafter as its "retracted position."

An opposing clutch member 33 is rigidly 95 mounted upon the end of the motor shaft 15 which extends beyond its bearing 16 toward the generator, a clutch disk 34 being thus disposed face to face with the clutch disk 30, the faces of these disks lying in 100 planes at right angles to the axes of the shafts which, as before stated, are co-incident. The arrangement is such, as shown in the drawings, that when the clutch disk 30 is in its retracted position, it is slightly 105 spaced from the clutch disk 34 which is not

capable of longitudinal movement upon its shaft. It will be seen, however, that the longitudinal movement of which the disk 30 is capable will permit that disk to be moved into face-to-face contact with the disk 34, and the means by which this operation is secured will be described presently.

The face of the disk 34 is provided with an annular groove 35 in which a coil 36, of properly insulated wire, is disposed. On the back of the clutch disk 34 an annulus 37, of insulating material, is secured, and mounted upon this insulating material are two rings 38 and 39, to each of which one of the leads of the winding 36 is attached, as illustrated. The clutch disks are constructed of magnetic material and it will be seen that when the winding 36 is energized, the part 34, which acts as a core, becomes magnetized and attracts the opposite disk in the manner of the operation of an armature. In order to connect the energizing winding 36 in the circuit, each of the rings 38 and 39 has coöperating therewith a brush 40 which slides on the surface of the respective ring when the disk rotates with the motor shaft. Each brush 40 is supported in a bracket 41, and leads 42 and 43 from the motor circuit are provided in connection with the respective brushes. It will be seen that I have opened the motor circuit between one of the field windings and one of the commutator brushes and have electrically inserted the winding 36 therein.

A storage battery 44 is provided and the generator terminals are connected with the terminals 45 and 46 of this storage battery by means of conductors 47 and 48 respectively. One terminal of the motor circuit is also connected with the terminal 45 by means of a conductor 49, through a switch 50, which I have illustrated diagrammatically and which is intended to represent any conception of a switch, since my invention is not concerned with the particular and specific construction of this device. The other terminal of the motor circuit is connected with the terminal 46 of the storage battery by means of a conductor 51.

The switch 50 is normally open. When the engine is running in its regular operation the movement of the fly-wheel 28 is transmitted to the pulley 27 and to the generator shaft. The generator is operated for the purpose of charging the storage battery 44. It will be remembered that in this condition the clutch members 30 and 34 are separate, as illustrated in Fig. 1. Let it be assumed, therefore, that the battery 44 is charged.

When it is desired to start the engine from a condition of rest, the switch 50 is closed and the battery voltage is thrown onto the motor terminals. Since the inertia of the motor armature delays its response to

the attraction of the motor fields, there will be a large and unrestricted flow of current through the magnetic clutch winding 36.

This will immediately attract the clutch disk 30, which has but a very short distance to move, and the armature of the motor is further loaded by the resulting mechanical connection of the generator and the engine. However, the motor armature responds eventually, (I say eventually, since it is eventually, analytically, although, as a matter of time, the period is extremely short), and begins to rotate and, since the clutch disks are now in firm contact, carries the pulley 27 with it and, consequently, turns the fly-wheel 28 of the engine. It is assumed, of course, that the engine conditions are such that the turning of the fly-wheel will result in the starting thereof, as is well-known in the art, and, when the engine has developed its own movement, the load is removed from the motor shaft and, due to the inductive effect of the rotating armature, a counter-electromotive force of relatively high value is developed in the motor circuit. The result is a prompt drop in the current and a corresponding reduction in the attractive effect of the clutch disk 34. Consequently, the clutch disk 30 is released from the clutch disk 34 and the function of the motor has been performed. The spring 32 is provided to insure the separation of the clutch disks and, after the engine is started, the switch 50 may be opened to restore normal conditions with the engine running and the generator charging the battery. If conditions are such that the drop in the current, due to the response of the motor armature, is not sufficient to release the clutch, when the engine takes hold the motor armature will not only be relieved of its load, but it will be operated by the engine faster than it would operate itself (due to the engine speed) and it is there operated as a generator armature and the counter-electromotive force will be all the more pronounced to the extent of reversing the current in the clutch to effect the release of the clutch with certainty.

In Fig. 2 I have illustrated an arrangement similar to Fig. 1, except that I have taken the precaution to provide special means for keeping the motor armature at rest until the clutch is closed, so as to insure the presence of sufficient current to compel the catching of the clutch. I have provided the analogous parts in Fig. 2 with the same reference characters as in Fig. 1, and it will be seen that on the back of the clutch disk 30 I provide an insulating disk 52, upon which I mount a short-circuiting ring 53, with which two spring brushes 54 and 55 are normally in contact. These brushes are insulated from each other and are operated in a bracket 56 extending from the motor

casing. One of these brushes is connected with one of the brushes of the motor commutator and the other brush is connected with the other brush of the motor commutator. When the clutch disk 30 is in its retracted position, the motor armature is thus short-circuited and it cannot respond until the short-circuit has been opened. The spring brushes 54 and 55 are so arranged that they will follow and keep in contact with the ring 53 until just before the disk 30 has come into firm mechanical engagement with the disk 34. The final movement of the disk 30 in its attraction to the disk 34, results in the separation of the brushes from the ring and the armature is then free to respond. The building up of the counter-electro-motive force is, therefore, delayed and by the time sufficient counter-electro-motive force has been developed to cause the release of the clutch, the engine is well under way.

In Fig. 3 I illustrate another arrangement. Here the clutch disk 30^a is securely mounted upon the generator shaft, while the clutch disk 34^a is capable of slight longitudinal movement on the motor shaft, although it always rotates therewith. Under normal conditions the separation of the clutch disks is insured by means of a spring 57, which is disposed in a pocket in the end of the generator shaft and which abuts against an axially disposed ball 58 resting in a slight depression 59 in the disk 34^a. The axial location of this ball is desired to eliminate any turning moment on the spring. The electrical operation of this modified structure is the same as described with reference to Fig. 1. The energization of the winding in the disk 34^a, which in itself is exactly similar to the disk 34, results in the movement of the disk 34^a toward and into contact with the disk 30^a. In this modified structure, however, the brushes 40, 40 have respectively associated therewith heavy springs 60, 60, and these springs bear down on the rings 38 and 39 heavily enough to place a comparatively heavy load on the motor armature until the clutch 34^a has been brought into firm mechanical contact with the clutch 30^a. Of course, the spring 57 is of greater strength than the springs 60, 60. The springs 60, 60 continue to bear heavily upon the rings until just before the clutch catches, when substantially all of their effect is removed. In this way the building up of the counter-electro-motive force to cut down the current to release the clutch is certainly delayed until the engine is under way.

In Fig. 4 the arrangement is the same as in Fig. 3, except that instead of providing springs 60, 60 in direct association with the brushes 40, 40, separate springs 61, 61 are provided for the same purpose. Each of the springs 61 operates against the head 62 of a plunger 63, (Fig. 5), and this head 62 bears against a plate 64 carried on the back of the clutch disk 34^a when this clutch disk is in its retracted position. When the clutch disk 34^a moves over into contact with the disk 30^a, the heads 62, 62 of the plungers continue to bear upon the plate, but their movement in response to the springs is arrested just before or just at the time the two disks are in contact. This is accomplished by the means illustrated in Fig. 5, where it will be seen that the plunger carries a pin 64' which operates in the cylinder 65 extending from the motor frame. The arrangement is such that the pin reaches the end of the slot at the time just referred to. The exteriors of the cylinders 65, 65 are screw-threaded for the reception of adjusting nuts 66, whereby the tension of the springs is adjusted.

In Fig. 6 I have shown a modified form of clutch disk in which the slot containing the energizing winding, instead of being annular, is spiral, as illustrated at 67. This arrangement secures somewhat more effective magnetization.

In Fig. 7, I have illustrated a structural arrangement of the motor and generator which is similar to that of Fig. 1, except that the pulley or pinion is on the outside.

In Figs. 8 and 9, I have illustrated an arrangement wherein the motor is superimposed upon the generator, each being provided with a sprocket. These sprockets are connected together and to a sprocket carried with the fly-wheel in the manner illustrated in Fig. 9.

In Figs. 10 and 11, I have illustrated still another arrangement. In this structure the motor is superimposed upon the generator and the gears of the two units are mechanically connected by an idler 68, the generator being provided with a sprocket connected with the sprocket on the fly-wheel. This arrangement is especially desirable because any speed relation between the motor and generator shafts may be had.

I show these various arrangements to illustrate the flexibility of the structure of my invention and to instruct those skilled in the art how to best avail themselves of the space which they may have for the setting of an engine starter in an automobile, for instance, wherein my invention will probably find its most popular employment.

In Fig. 12 I have illustrated a modified arrangement which may be applied to Fig. 1. The other parts are the same as illustrated in Fig. 1, but it will be seen that the switch 50 is controlled by a spring 75 normally operating to hold the switch off its contact. An electro-magnet 76 is inserted in the conductor 49 and the core of this electro-magnet, when energized, is adapted to hold the switch arm 50 in engagement with

its contact. It will now be seen that if the switch is closed manually, it will be automatically locked in position by the energization of the electro-magnet. When the drop 5 in the current occurs, as heretofore described, the electro-magnet will release the switch arm and the clutch motor circuit will be opened. The core of the electro-magnet may be polarized to make the action more pronounced and the additional effect of the counter-electro-motive force is void here, as heretofore described with reference to the clutch coil.

In Fig. 13 I have illustrated an arrangement wherein the end of the motor frame 12 is faced off and the rotary disk 34^b of the clutch is placed in very close juxtaposition to the motor frame. In this way the magnetic effect of the field frame of the motor is 15 transmitted to the clutch member 34^b and it is energized at the time the circuit is closed, just as if it were provided with a winding, as previously described. Such energization draws up the clutch member 30 20 to operatively connect the motor with the engine.

What I claim as new and desire to secure by Letters Patent is:

1. In combination, an engine, a series-wound direct-current electric motor, a rotary member normally disconnected from said motor but connected to the engine, and an electromagnetically-operated clutch for operatively connecting said motor and said 30 rotary member, the energizing winding of the clutch being included in the motor circuit and said engine being adapted to operate the armature of said motor at such speed that the counter-electromotive force will exceed the applied electromotive force to effect 35 reversal of current in said clutch to release it.

2. In combination, an engine, a series-wound direct-current electric motor, a rotary member normally disconnected from 40 said motor but connected to said engine, an electromagnetically-operated clutch for operatively connecting said motor and said rotary member, the energizing winding of the clutch being included in the motor circuit,

and means for reversing the current in said clutch to cause its release.

3. In a starting mechanism, the combination with an engine member, an electric motor, and a member connected to said motor for coaxing with the engine member, of an 55 electromagnet for controlling the second member, a switch for controlling the motor and the electromagnet, and means for temporarily retarding the operation of said motor upon the closing of said switch to complete the normal circuit of said motor.

4. In a starting mechanism, the combination with an engine member, an electric motor, and a member for operatively connecting said motor to said engine member, 65 of means in circuit with the motor for controlling the engagement of said motor member with the engine member, and means for temporarily modifying the operation of the motor upon the closure of its normal circuit. 70

5. In a starting mechanism, the combination with an engine member, an electric motor, and a member for operatively connecting said motor to said engine member, of means in series with the motor for controlling the engagement of said motor member with the engine member, and means for temporarily modifying the operation of the motor upon the closure of its normal circuit. 75

6. In a starting mechanism, the combination with an engine member, an electric motor, and a member for operatively connecting said motor to said engine member, of means in series with the motor for controlling the engagement of said motor member 80 with the engine member, and means for temporarily modifying the operation of the motor upon the closure of its normal circuit in order to prevent relative rotative movement of said members while their engagement is 85 being effected.

In witness whereof, I hereunto subscribe my name this 6th day of September, A. D. 1913.

GEORGE M. WILLIS.
